UNITED STATES PATENT OFFICE.

CHAUNCEY T. KEEFER, OF STANFORD UNIVERSITY, CALIFORNIA.

ORIGINAL PACKAGE FOR CIGARS OR CIGARETTES.

Application filed April 2, 1924. Serial No. 703,697.

To all whom it may concern:

Be it known that I, CHAUNCEY T. KEEFER, a citizen of the United States, residing at Stanford University, in the county of Santa Clara and State of California, have invented certain new and useful Improvements in Original Packages for Cigars or Cigarettes, of which the following is a specification.

10 Tobacco products, particularly cigarettes, have been heretofore packed in original packages preferably of a flexible paper construction, the packages being torn open at their ends to permit access to be had to the cigarettes and to admit of their being withdrawn endwise therefrom. These packages have many disadvantages, the most pertinent being that after the end is once torn open, the cigarettes drop therefrom through 15 the opening and become damaged and unfit for use; another being that when but two or three cigarettes remain in the package, the body of the package is not sufficient to prevent the cigarettes from becoming 20 broken, due to the collapsing and twisting of the side walls of the package. Boxes in the form of original packages have been employed, each consisting of a receptacle part and a lid, the cigarettes being positioned in the receptacle part in superimposed layers and removable therefrom by a side- 25 wise movement on the raising of the lid and the holding of the receptacle in a substantially horizontal position.

30 The object of my invention is to provide an original package for cigarettes which is attractive and novel, differing from the conventional forms now in use, and which may be cheaply manufactured, and which 35 when opened is held with its faces in a substantially vertical plane presenting the cigarettes to the smoker in an endwise position in a manner similar to that presented by the use of the more expensive cigarette 40 cases. Another object is to provide an original package which is relatively flat, and which will fit within the coat or vest pocket without bulging, and one which will prevent the cigarettes from being damaged 45 either when the receptacle is filled or nearly empty.

50 My improved original container for tobacco products, particularly cigarettes, consists of a substantially rigid package of paper, board or composite material construction consisting of complementary half sec-

tions each forming a receptacle, the sections being hinged together along one edge in such manner as to permit the free edges of the sections to contact when the parts are 60 in closed position. The cigarettes, when the free edges of the half sections are swung into open position, are by my improved original container construction, presented in an endwise relation, one or more layers in 65 each half sections, admitting of the holding of the package in one hand with the hinged portion resting in the palm of the hand between the thumb and finger, and with the construction in a substantially vertical position, thus admitting of the ready 70 grasping and endwise withdrawal of the desired cigarette when the free edges of the complementary half sections are permitted to separate and the package to become open. It is preferred that each half section of my 75 original container be lined with a sheet of foil or wax paper to preserve the humid condition of the cigarettes, and that this lining be permanently secured to the receptacle sections. It is a further object to incorporate 80 a cigarette retaining strip disposed parallel with the hinge portion one co-operating with each complementary section for providing a package in each complementary section for 85 retaining the cigarettes, and a further object is to provide an elastic retaining means preferably secured to the exterior surface of one complementary section for stretching to embrace both sections and retain their 90 meeting edges in contact when it is desired to maintain the package closed.

With the above mentioned and other objects in view, the invention consists in the novel construction and combination of parts 95 hereinafter described, illustrated in the accompanying drawings, and set forth in the claims hereto appended, it being understood that various changes in the form, proportion, size and minor details of construction 100 within the scope of the claims may be resorted to without departing from the spirit or sacrificing any of the advantages of the invention.

To more fully comprehend the invention, reference is directed to the accompanying drawings wherein:

Figure 1 is a view in perspective of the preferred embodiment of my invention disclosing the receptacle in closed position.

Figure 2 is a view illustrating the receptacle in opened position and disclosing one

complementary section containing cigarettes, and the other one empty.

Figure 3 is a cross sectional view disclosing the manner of arranging the cigarettes in the respective complementary sections, the dotted lines indicating the elastic retaining member.

Figure 4 is a view in detail section of one of the complementary sections illustrating the lining and disclosing an out-turned peripheral edge.

Figure 5 is a view similar to Figure 4 illustrating an inturned peripheral edge.

In the drawings, wherein like characters of reference designate corresponding parts, the numerals 1 and 1' designate the complementary receptacle sections each consisting of side walls 3 and end walls 2 disposed at substantially right angles from the face of the back or bottom wall 4 of the respective sections. The walls 2 and 3 connect at their ends and are preferably disposed at right angles to each other. The complementary sections 1 and 1' may be of built up structure or may be cast or moulded from composite or pulp material, cheapness and rigidity in manufacture determining the exact construction to be employed commensurate with the size of the package desired. The side walls 3 of the complementary sections 1 and 1' are hinged together as at 5 by a flexible strip uniting the sections to form a container or package so constructed that the edges of the remaining side wall 3 and end walls 2 of the complementary sections will contact as in Figure 3 when the sections are moved to closed position. Each section is provided with a lining 6 of suitable flexible sheet material, such as foil or wax paper to preserve the quality of the contents of the package, and this sheet material is securely held in position in the respective complementary sections as by adhesive or glue or in any other suitable manner. Uniting the free edges of the end walls 2 of the respective sections 1 and 1' with their edges disposed parallel with the axis of the hinge strip 5 are the cigarette retaining strips 7 of any suitable material such as paper. These strips retain the cigarettes within the respective complementary sections 1 and 1' in parallel relation with one end disposed adjacent to the hinge strip 5, this arrangement positioning the other end of each cigarette adjacent that edge of the respective sections removed from the hinge strip. A suitable means for retaining the complementary sections in closed

position is employed and in this embodiment the same consists of an elastic 8 held to one of the sections in any suitable manner as at 9, and the elastic is adapted to be stretched around the complementary sections when the meeting edges thereof are in contact to retain the receptacle in closed position. Any suitable printed or advertising matter 10 may be associated with the exterior surface of the package.

The package being assembled as in the drawings and the cigarettes being packed therein as illustrated, the operator in using the package removes the elastic 8 from around both complementary sections, positions the hinged portion 5 of the sections in the palm of one hand, and opens the receptacle by separating the free edges of the complementary sections from each other. This presents to the smoker two rows of cigarettes in endwise relation and admits of his selection and endwise withdrawal of the desired cigarette from the package.

Having thus described my invention, what I claim as new and desire to protect by Letters Patent of the United States is:—

An original package for cigarettes or the like comprising two complementary half sections, a flexible strip uniting said sections along one edge and constituting a hinged connection, each half section comprising a self sustaining fibrous body including a bottom and side and end walls extending at substantially right angles therefrom with the co-operating ends of the side and end walls disposed at substantially right angles to each other, providing a receiving recess in each section, the peripheral edges of each side and end wall contacting when the half sections are in closed position, a strip of material disposed parallel with the hinge forming strip and uniting the free edges of opposing walls of the respective sections and extending across the respective recesses for retaining cigarettes in said recess in parallel relation, an endless elastic member secured to one of the half sections and adapted for stretching to embrace the half sections and retain the same in closed position with their edges in meeting relation, and a moisture proof lining covering the inner face of each half section said lining secured to the peripheral edges of said half sections.

In testimony whereof I have signed my name to this specification.

CHAUNCEY T. KEEFER.
